UNITED STATES PATENT OFFICE.

JAMES HASLAM, OF BOLTON, ENGLAND.

DRIVING-ROLLER.

SPECIFICATION forming part of Letters Patent No. 678,175, dated July 9, 1901.

Application filed October 22, 1900. Serial No. 33,954. (No model.)

To all whom it may concern:

Be it known that I, JAMES HASLAM, tin-plate worker, a subject of the Queen of England, residing at Romer street, Touge, Bolton, in the county of Lancaster, England, have invented 5 certain new and useful Improvements in Driving-Rollers, of which the following is a specification.

This invention refers to improvements in 10 or relating to tinned iron and other rollers, and means for coupling, supporting, and strengthening the same, and it includes certain novel features hereinafter described and claimed.

15 Figure 1 is a longitudinal sectional elevation of my improvements in the rollers employed for driving the spindles of mules, throttle-frames, and other textile machinery, such as ring-frames, winding-frames, and the like; 20 Fig. 2, a longitudinal sectional elevation of my improvements wherein the ends of two rollers are coupled together; Fig. 3, an end view of Fig. 1; Fig. 4, a reduced plan of my improvements in rollers and the means and 25 method of driving the same; and Fig. 5, an end view of Fig. 4, showing the endless band for driving the said rollers and keeping them in unison.

30 A represents the tinned iron or other metallic rollers; B, cast-iron or other metallic bosses cast to the circular ends; C, circular ends; D, centers for carrying the tinned iron or other metallic rollers to be mounted in the usual bearings located on the framework of the machines to which they are applicable; E, centers for coupling the tinned iron or other metallic rollers together, according to the number required in a machine or frame; F, endless driving band or rope, and G carrier-pulleys. 35

40 In all the figures the same letters are employed to indicate corresponding parts.

To each end of the tinned iron or other metallic roller A is attached the tinned iron or other metallic circular end C, provided with the curved edge or periphery I, in which is located the wire or metallic strengthening-ring H, the curved edge or periphery I being formed so as to allow of the end or edge of 45 the tinned iron or other metallic roller A abutting against the wire or strengthening-ring 50

H, after which the end of the said roller A and the circular end C are secured together in the usual manner by means of solder. The circular ends C are constructed with the circular indents J for the purpose of strengthening the same and preventing "buckle." After the circular ends C have been constructed in the form or manner set forth and as shown in the drawings they are secured to 55 the cast-iron or metallic bosses B during the operation of casting the latter, being placed in the "mold" prior to running in the molten metal. To insure of the circular ends C being thoroughly secured to the cast-iron or 60 metallic bosses B, they are provided with the holes K, through which the molten metal flows in forming the flanges L, as shown in Figs. 1 and 2. In constructing the ends of the tinned iron or other metallic roller A with the 65 band or rope pulley M the latter is made in halves circumferentially, as shown in Fig. 1, one half being provided with the bent end a, which overlaps the curved edge or periphery I of the tinned iron or other metallic circular 70 end C, and to which it is secured by means of solder. To the periphery N of the rope or band pulley M is secured the other half or side f by means of solder at c, and the projecting end d is bent over the inner periphery of the 75 half or side f of the rope or band pulley M, after which it is secured by means of solder at e, thus forming the rope or band pulley M, as shown in Fig. 1. The upper end of the side f of the rope or band pulley M is provided with the curved edge or periphery g, in which is located the wire or metallic ring h for the purpose of strengthening the same. 80

The center E, employed for carrying and connecting the ends of the tinned or other rollers A together, is mounted in the bearing R, attached to the cross-bar S, supported from any suitable or convenient part of the machine or frame to which this invention may be applied. The centers D and E are secured 90 in the bosses B by the set-screws W, as shown in Figs. 1 to 3, inclusive.

The tinned iron or other metallic rollers A are rotated in the direction indicated by the arrows, as shown in Fig. 5, the endless driving band or rope F being carried and guided 95 by the carrier-pulleys G, mounted on the 100

centers V, the latter being supported in fixings or bearings attached in any suitable manner to any convenient part of the machine or frame to which they may be applied. To facilitate balancing and the true rotary motion of the rollers A, the bosses B are provided with the projection X to equalize the weight of the boss *t* and the projecting portion of the set-screws W. If desired, the bosses B may be "split" and secured by rings, bolts, set-screws, and the like.

The wires H and *h* may be tinned to facilitate annealing for strengthening purposes.

Having now particularly described and ascertained the nature of my said invention and in what manner the same is to be performed, I declare that what I claim is—

1. A roller A having the metallic circular end C provided with the circular indent J and the curved edge or periphery I, the strengthening-ring H within said curved edge and against which abuts the end or edge of said roller, said circular end C having holes K, a cast-iron boss B having flanges overlapping

the end C, a shaft E, and set-screws to secure the boss to said shaft.

2. A metallic roller A having attached thereto, a metallic circular end C provided with a circular indent J and the curved edge or periphery I, the strengthening-ring H within said curved edge and against which the end of said roller A abuts, the band or rope pulley M made in halves circumferentially one half being provided with the bent end *a* to overlap the curved edge or periphery I the other half of said pulley having a curved edge, a strengthening-wire inside said last-mentioned curved edge, and said circular end C having holes K, and a boss B having flanges L to overlap said circular end.

In testimony whereof I have hereunto set my hand in presence of two subscribing witnesses.

JAMES HASLAM.
